UNITED STATES PATENT OFFICE.

ANTONIO A. FORTUNATO, OF BOSTON, MASSACHUSETTS.

HEEL FOR WOMEN'S SHOES.

1,417,156.

Specification of Letters Patent. Patented May 23, 1922.

Application filed July 21, 1920. Serial No. 398,008.

To all whom it may concern:

Be it known that I, ANTONIO A. FORTUNATO, a citizen of the United States, residing at Boston, in the county of Suffolk and State of Massachusetts, have invented a new and useful Heel for Women's Shoes, of which the following is a specification.

The object of my invention is to provide a novel metal heel for women's shoes having novel means for attaching and fitting the heel to the shoe, and having novel means for securing a leather lift to a filling contained within a chamber in the lower portion of the heel. I obtain the objects of my invention by the mechanism illustrated in the accompanying drawings, in which—

Figure 1 is a vertical section of the heel applied to a shoe;

Fig. 2 is a perspective view of the heel and attaching plate detached from the shoe;

Fig. 3 is a transverse section through the heel on line 3—3 of Fig. 1; and

Fig. 4 is a perspective view of the bottom of the heel before the leather lift has been applied.

Like numerals designate like parts in each of the several views.

Referring to the accompanying drawings I provide a metal heel 1, the main portion of which is hollow, and which is provided with a substantially U-shaped groove in the upper portion of the heel, as shown in Fig. 2, and which groove is adapted to receive the correspondingly shaped edge portion 4 of a metal attaching plate 3. Plate 3 is provided with prongs 17 which engage and mark the bottom of the shoe as shown in Fig. 2. After the heel has thus been properly positioned it is separated from the attaching plate and the latter is nailed or tacked on to

the shoe by suitable tacks 9 through openings 8. The heel is then slid into position engaging the plate 3 as shown in Figs. 3 and 1, and screws 7 are applied, these screws passing through openings 6 in plate 3 and through the corresponding openings in ears 5 of the heel 1. In other words the screws are inserted down through the bottom of the heel from the inside of the shoe and lock plate 3 and heel 1 together.

I further provide novel means for attaching a leather lift to a metal heel of this type. For this purpose I provide a chamber 11 in which I insert suitable pieces of leather 12. Members 12 are secured in place by a longitudinally extending screw 13 which is inserted from a lower portion of the breast of the heel, as shown in Fig. 1, and which is prevented from working loose by means of a small pin 14 which is inserted in a suitable aperture in the screw as indicated in Fig. 1. A leather lift 15 is attached by nails 6 which are driven through the lift 15 and into the leather filler members 12.

What I claim is:

In combination with a shoe, a metal plate secured to the shoe, a hollow metal heel slidably engaging the metal plate, the metal heel having inwardly extending apertured projections under the metal plate, the metal plate having apertures positioned to align with the apertures in the aforesaid projections when the heel is engaged on the metal plate, said apertures being threaded, and screws inserted through the interior of the shoe at the heel and securing the heel in rigid engagement with the metal plate, substantially as shown.

ANTONIO A. FORTUNATO.
